RAZOR

Arthur J. Briggs, Syracuse, N. Y., assignor to
 Magazine Repeating Razor Company, New
 York, N. Y., a corporation of New Jersey

Application January 31, 1941, Serial No. 376,774

13 Claims. (Cl. 30—40)

The invention relates to razors of the so-called "magazine" type and more particularly to a construction that may be used with blade packs having the characteristics of those to be described.

One of the objects of the invention is a razor with which can be used a blade pack of compact form and make-up that utilizes inexpensive containers or wrappers.

Another object is to enable the user to load the magazine with loose blades which however are provided with means for preventing easy dislodgment of one from another and whereby the pile of blades will be maintained in fixed position in the magazine except as they are ejected one by one as needed from the magazine into the shaving head of the razor.

Other objects will appear in the course of the description of the invention.

Describing the drawings:

Fig. 1 is an isometric view of the assembled blade pack suitable for use with the razor including in dotted lines a separate view of the retaining clip;

Fig. 2 is a view in elevation of the pack partly in section;

Fig. 3 is a view on the line 3—3 of Fig. 2;

Fig. 4 is a sectional longitudinal view of the razor with the blade pack therein;

Fig. 5 shows the bottom plate of the pack and the lifting spring;

Fig. 6 is an isometric view of the razor with the breech open showing how the stack of blades is introduced into the razor;

Fig. 7 is a view on the line 7—7 of Fig. 4;

Fig. 8 is a view on the line 8—8 of Fig. 4;

Fig. 9 is a view on the line 9—9 of Fig. 4;

Fig. 10 is a view illustrating the method of introducing a blade into the head of the razor;

Fig. 11 is a view showing the positions of the parts when the blades of the pack have been exhausted;

Fig. 12 is a view showing the head of the razor in closed or non-shaving position;

Fig. 13 is a view showing the head of the razor in shaving position.

Referring more in detail to the drawings, a preferred type of blade that may be used to make up the pack is illustrated in Figs. 2, 3, and 4. The blade shown is of a well-known conventional shape but is distinguished from such blades in that it is provided with two depressions or indentations 10 and 11, the process of producing these indentations (which may be accomplished by the use of a punch and die) creating nubs on the opposite side of the blade. The blades are all alike, and the nubs are similarly and uniformly positioned on all of them so that, when the blades are stacked or piled, the nubs of each blade nest in the indentations of the blade next below it, except of course in the case of the bottom blade, the nubs of which nest in the bottom plate as

will be presently explained. Each blade is therefore definitely located with respect to blades adjacent to it, although since the nubs and indentations are of approximately spherical contour a slight force is sufficient to dislodge them and to cause the blade to which the force is applied to slide on the one with which it contacts. The contour of the indentations and nubs is however not invariable, the particular contour shown being selected merely because of its metal-working advantages coupled with the fact that it satisfactorily functions to locate the blades with respect to each other and at the same time offers a yielding instead of a positive resistance to dislocation. However, it will become apparent as the description continues that, while it should be possible to dislodge a blade for lengthwise movement in one direction, it may if desired be positively prevented against dislodgment in the opposite direction. The manner in which the nubs and indentations function is illustrated in Figs. 2, 3, and 4. The number of blades in the stack is a matter of choice, although limited of course by the capacity of the chamber of the razor into which they are to be inserted.

The stack of blades preferably rests upon a plate 12 (Fig. 5) provided, as in the case of the blades, with indentations indicated by the numerals 13 and 14 located to register with the nubs on the bottom blade of the stack. The tongue 15 projecting from one end of the plate tips slightly down (as viewed in the drawings) and likewise the opposite end 16. In addition, two tongues 17, 17 are struck downwardly to serve as abutments to cooperate with the lugs 18, 18 projecting laterally from the lifting spring 19 (Fig. 5). The functions performed by the bottom plate and the spring will be later explained. In assembling, the stack of blades rests on the plate 12, the nubs of the bottom blade registering with the indentations 13 and 14 of the plate.

To retain the stack and the plate in assembled condition whereby it will resist forces tending to dis-assemble it, I provide the clip 20 (Figs. 1 and 6), whereby it will resist casual forces, which is of resilient material, such as steel or hard brass, the clip being (as in the case of the blades) provided with indentations and corresponding nubs 21, 21, although in this case only the nubs function. These nubs register with the indentations in the top blade of the stack. The clip is of U-shape as shown with the legs of the U normally turned inward toward each other so that, when stressed to grip the stack as shown, the latter will be tightly clamped. The bottom leg of the clip is provided with a longitudinal groove 22 into which the nubs of the plate 12 project and whereby the lower leg of the clip is maintained in a fixed position laterally.

The razor combines a shaving head generally

designated by the letter "A" mounted on a post 23 projecting from a hollow handle, generally designated by the letter "C," which serves as a magazine for containing the blade stack and also the mechanism for ejecting blades therefrom. It consists essentially of an elongated boxlike structure closed at one end except for the presence of the blade-ejection orifice 24 and open at the opposite end to permit the blade-inserting and blade-ejecting mechanism to be operated.

A blade stack container indicated generally by the letter "B" is slidably encased in the chamber within the handle. This container is essentially a box with the sides 25 and 26 and the end wall 27, the top being open and the bottom being apertured as at 28 to permit the lifting spring to free itself and drop to the bottom of the container when the latter is withdrawn from the chamber in which it is enclosed. To explain, it is to be noted that the lifting spring 19 pivotally engages the ends of the side walls of the box by means of the shoulders 29, 29. When the container is within the chamber, the free end 30 of the lifting spring rests on the bottom of the chamber and the spring bows upwardly as shown in Fig. 11, where the container is emptied of blades and, as shown in Fig. 4, where a full stack of blades is within the container. The normal shape of the spring when in an unstressed condition is approximately as shown in Fig. 5. When the blade container is withdrawn from the chamber, the free end 30 of the lifting spring drops through the aperture 28 in the bottom of the container and down over the end of the bottom wall of the chamber, and therefore its presence does not interfere with the insertion in the container of a stack of blades. Clearance is provided between the upper edge of the end wall 27 and the top wall of the casing in order to permit of the passage of a blade and also of the plunger from the magazine through the blade ejection orifice 24. This end wall is centrally notched as shown in Figs. 7 and 11 so that the nubs on the blades will pass freely through.

A closure for the container and also for the open end of the razor handle is supplied by the block 31 pivoted to the container by the trunnions 32, whereby, when the block carrying with it the container is withdrawn to the position shown in Fig. 6, it drops down or may be swung down to permit of the insertion in the container of a blade pack also as shown in Fig. 6. It will be observed that the block 31 has a slightly inclined surface 33 (Figs. 4 and 6), the purpose of which is to insure a certain and easy entrance when the block (with the container) is moved into the chamber from the position shown in Fig. 6 to the position shown in Fig. 4. The plate 34 retained in position by the rivets 34a and 34b is simply an expedient for establishing a hinged connection between the block 31 and the blade container.

Ejection of blades one by one through the blade-ejection orifice 24 is effected by means of the plunger 35, which is slidably mounted within the handle so that it can be reciprocated between the positions shown in Figs. 4 and 11 in line with the blade-ejection orifice. It is channel-shaped, the edges of the flanges of the channel sliding along the upper edges of the container, and rear support and freedom of motion are permitted by the fact that it slidably rests on the block 31. To limit its rearward stroke, an outwardly projecting spring tongue 36 is pro-

vided, which on withdrawal of the plunger abuts against the indentation 36a (Fig. 7) in the inside of the wall of the chamber. The container itself may also be provided with a similar spring tongue 37 which enters an indentation in the wall of the chamber and operates in a similar way to limit the extent to which the container may be withdrawn from the chamber.

The shaving head (see Figs. 4, 7, and 9) is pivoted to the post 23 so that it can be swung to the position shown in these figures to receive a blade and then to a position perpendicular to the post for shaving purposes. It consists essentially of a bottom plate 38 and a blade 10 clamping plate 39, which may be angular extensions of the plates 40 and 41 through which the pivoting screw 42 passes, whence it is threaded 15 in the post. The usual guard 43 is, of course, provided. In the blade-supporting surface of 20 the bottom plate 38 there is provided a longitudinal groove 44 in which the nubs of a blade travel in the course of being injected into the 25 shaving head. The position of this groove laterally with respect to the guard is such that, when the nubs of a blade are located in it, the 30 edge of the blade bears a correct or desired positional relationship to the guard, and thus blades are all uniformly positioned in the head. Of course, on the other hand, the position of the 35 groove may be first fixed and then the blades may be manufactured with the nubs positioned to correspond with the position of the groove.

The groove 44 registers with the groove 45 in 33 the end wall 46 of the handle and thus the nubs 38 of the blade being ejected travel in it and thence into the groove 44. To properly guide the blades 40 into the groove 45 its entrance may be slightly widened as shown at 47. It will be observed (see Fig. 7) that one corner of the container is formed 45 to exhibit a diagonally extending facet, as shown at 48, and that (see Fig. 6) the block 31 is provided with a flange 49 of triangular section. Thus, only the extreme ends of the cutting edge 50 of a blade in the container can contact with the wall of the container, which is course is desirable to insure that their edges shall not be injured.

The corners of the blades themselves are preferably cut away as shown in Fig. 6 but not sufficiently to permit the blade edge to contact with the side of the container. This is shown in Fig. 7.

By reference to Figs. 1 and 6, it will be understood how the pack may be assembled. The desired number of blades may first be stacked with 55 the nubs of each successive blade beginning with the top blade and nested in the indentations of the blade beneath and (if single edge blades) with the edges all on one side of the pile. The pile may be then placed on the bottom plate 12 with the nubs of the bottom blade nested in the 60 indentations 13 and 14 of the plate and with the tongue 15 at that end of the pack which first enters the blade stack container as the magazine is being loaded (see Fig. 6). The clip or 65 clamp (see Fig. 1) is then applied so that nubs on the upper leg of the U nest in the indentations in the uppermost blade and the nubs on the plate 12 register with the groove 22 on the lower leg of the U. The legs of the U point in the same direction as does the tongue 15. The blade stack container having been fully withdrawn as shown in 70 Fig. 6 and the closure block 31 being out of the way, the pack is then inserted in the container. The clip is then wholly withdrawn (to be discarded if desired), the cooperating nubs on the

upper leg being readily freed from the stack and leaving the stack together with the plate 12 in the container. To prevent withdrawal of the stack as the clip is withdrawn, the container is provided with a stop 50 against which the blade stack abuts as the clip is withdrawn, tending to carry with it, of course, the blade stack. However, this stop is located low enough so that it does not interfere with the introduction of the pack into the container. The stop 50 is best shown in Fig. 6, and it will be apparent that, in inserting a pack, the latter may be tilted upwardly sufficiently to clear the stop but that, when the pack has been fully inserted and lowered, the stop will prevent withdrawal of the stack although it does not interfere with withdrawal of the clip. The closure block 31 is relieved as shown at 31a so that it can be closed without interference from the stop. The clip having been withdrawn, the blade stack container, together with the closure block 31 (the latter being swung up in the process), is driven into the chamber to the position shown in Fig. 4. As this takes place, the spring 19 is dragged along the container, its free end trailing along the bottom of the casing, the result being that it is flexed from its normal shape as shown in Fig. 5 to a nearly flat shape, which causes a resilient upward pressure to be exerted against the blade stack. The uppermost blade of the stack is therefore always pressing against the plunger or against the top wall of the casing (i. e., in line with the blade ejection orifice) when the plunger is withdrawn. As blades are fed one by one from the stack, the stressed spring follows upwardly until the last blade has been ejected. In order to insure that the last blade shall not be dragged backwardly by the friction of the plunger as the latter is withdrawn, the lugs 18, 18 may be provided on the spring against which the tongues 17, 17 abut, there being enough flexibility in the spring to allow the lugs 18, 18 to travel upwardly in a perpendicular plane.

Actual ejection of the topmost blade of the stack is effected by first fully retracting the plunger, whereupon the topmost blade rises to alignment with it and with the ejection orifice, and then advancing the plunger to the position shown in Fig. 4. This action dislodges the topmost blade from the one beneath it, and it is driven into shaving position in the head, guided to proper relation with the guard because its path is fixed by the nubs traveling in grooves 44 and 45. If it is desired then to use the implement for shaving, the shaving head is swung to a position crosswise of its supporting post.

The blades all maintain their positions fixedly with respect to each other by virtue of the nesting of the nubs and indentations, a condition which is maintained by the pressure of the lifting spring 19.

When the bottom blade of the stack has been ejected, the bottom plate 12 has risen to the top of the chamber as shown in Fig. 11. On withdrawal of the closure block and blade stack container, the bottom blade may be dropped out or manually removed. It has previously been noted that the ends of the bottom plate are tipped downward slightly. This is to prevent its being ejected through the blade discharge orifice. If it is attempted to so eject it, the tip of the plunger rides over the end 16 instead of abutting with it as in the case of a blade. But even if there is any tendency to eject it through the orifice and by reason of frictional contact between it and the plunger, the tipped-down tongue 15 abuts

against the end wall of the blade stack container which positively prevents it from passing into the blade ejection orifice.

Figs. 12, 13, and 14 illustrate an adaptation of the invention to the type of razor with which a separate magazine is employed. The parts indicated generally by the letter "E" are in all respects similar to the parts indicated by the letter "C" in Fig. 4. However, in place of the shaving head mounted on the post as shown in Fig. 4, there is provided an aligning finger 51 which is designed to enter an aligning slot 53 in the shaving head 52 and position the magazine and the shaving head with respect to each other so that a blade ejected from the magazine enters the blade channel in the shaving head. This shaving head as in the case of that shown in Fig. 4 has a bottom plate 38 and a blade clamping plate 39 and guard 43, together with a groove 44, in the bottom plate precisely as in the case of the permanently affixed shaving head. Razors of this type are as shown in Rodrigues United States Patent No. 1,969,945, issued August 14, 1934.

While I have described a certain particular construction in which my invention is incorporated, I do not desire to be limited to this particular embodiment since many changes and modifications may easily be made without departing from the spirit and scope of the invention as set forth in the following claims.

I claim:

1. A razor of the magazine type comprising a casing with an open end, a blade container slidably contained in the casing and likewise having an open end, and a member hingedly connected to the container and serving as a closure for both the open end of the container and the open end of the casing.
2. A razor of the magazine type comprising a casing with an open end, a blade container slidably contained in the casing and likewise having an open end, and a member hingedly connected to the container and serving as a closure for both the open end of the container and the open end of the casing, the container and the closure member being provided with abutments at opposite ends of the space confined by them against which two of the corners of a blade in the container will bear.
3. A razor of the magazine type comprising a magazine consisting of an elongated casing with an open end, a blade stack container slidably contained therein, said container consisting of a box with an open top and an open end, a closure for the said open end of the casing and of the container hingedly connected with the container, one corner of the container projecting into the interior thereof and the closure being provided with a flange projecting into the interior of the container when the closure is inserted in the casing.
4. A razor of the magazine type comprising a casing with an open end, the other end being provided with a blade ejection orifice, a blade container slidably contained in the casing and likewise having an open end, a member hingedly connected to the container and serving as a closure for both the open end of the container and the open end of the casing, and means for ejecting a blade in the container through the said blade ejection orifice.
5. A razor of the magazine type comprising a casing with an open end, the other end being provided with a blade ejection orifice, a blade container slidably contained in the casing and

likewise having an open end, a member hingedly connected to the container and serving as a closure for both the open end of the container and the open end of the casing, and means for ejecting a blade in the container through the said blade ejection orifice, said means comprising a reciprocably mounted plunger.

6. A razor of the magazine type comprising a casing with an open end, the other end being provided with a blade ejection orifice, a blade container slidably contained in the casing and likewise having an open end, a member hingedly connected to the container and serving as a closure for both the open end of the container and the open end of the casing, the container and the closure member being provided with abutments at opposite ends of the space confined by them against which two of the corners of a blade in the container will bear, and means for ejecting blades one by one from the container.

7. A razor of the magazine type comprising a casing with an open end, the other end being provided with a blade ejection orifice, a blade container slidably contained in the casing and likewise having an open end, a member hingedly connected to the container and serving as a closure for both the open end of the container and the open end of the casing, the container and the closure member being provided with abutments at opposite ends of the space confined by them against which two of the corners of a blade in the container will bear, and means for ejecting blades one by one from the container, said means comprising a reciprocably mounted plunger.

8. A razor of the magazine type comprising a magazine consisting of a casing with an open end, a blade stack container slidably contained in the casing and likewise having an open end, and a member serving as a closure for both the open end of the container and the open end of the casing, said member being hingedly connected to the container, the container being of dimensions to contain a stack of blades of predetermined size, the member being provided with a flange adapted to project into the container and to serve as an abutment against which a corner of a blade within the container will bear, the container being also provided with an abutment against which the opposite corner of the said blade will bear.

9. A razor of the magazine type comprising a casing with an open end, the opposite end being closed by an end wall except for the presence of a blade ejection orifice therethrough, a blade receiving shaving head being associated with the casing and adapted to be moved to a position at which the blade holding channel of the head is aligned with the said blade ejection orifice, one of the walls of the blade holding channel being provided with a groove running longitudinally of the guard, the end wall of the casing being provided also with a groove for guiding and definitely locating a blade provided with nubs projecting from its surface.

10. A razor of the magazine type comprising a casing with an open end, the opposite end being closed by an end wall except for the presence of a blade ejection orifice therethrough, a blade holding shaving head with a guard being associated with the casing and adapted to be moved to a position at which the blade holding channel of the head is aligned with the said blade ejection orifice, one of the walls of the blade holding channel being provided with a groove running longi-

tudinally of the guard, the end wall of the casing being provided also with a groove for guiding and definitely locating a blade provided with nubs projecting from its surface, the first-mentioned groove being aligned with the last-mentioned groove when the said blade holding channel is aligned with said blade ejection orifice.

11. A razor of the magazine type comprising a casing with an open end, the opposite end being closed by an end wall except for the presence of a blade ejection orifice therethrough, a blade holding shaving head with a guard being associated with the casing and adapted to be moved to a position at which the blade holding channel of the head is aligned with the said blade ejection orifice, one of the walls of the blade holding channel being provided with a groove running longitudinally of the guard, the end wall of the casing being provided also with a groove for guiding and definitely locating a blade provided with nubs projecting from its surface, and a razor blade in the casing provided with a plurality of nubs on one face thereof spaced longitudinally of the blade, and means for ejecting the blade through the blade ejection orifice and into the said blade holding channel with the nubs traveling in the grooves.

12. A razor of the magazine type comprising a casing with an open end, the opposite end being closed by an end wall except for the presence of a blade ejection orifice therethrough, a blade holding shaving head with a guard being associated with the casing and adapted to be moved to a position at which the blade holding channel of the head is aligned with the said blade ejection orifice, one of the walls of the blade holding channel being provided with a groove running longitudinally of the guard, the end wall of the casing being provided also with a groove for guiding and definitely locating a blade provided with nubs projecting from its surface, and a stack of razor blades in the casing, each blade being provided with a plurality of nubs on one face and a plurality of indentations in the other, the nubs of each blade being nested in the indentations in a contiguous blade, the nubs and indentations sloping away from the surface of the blade and toward one end thereof at an angle small enough so that a blade may by an endwise sliding motion be dislodged from the blade contiguous to it.

13. A razor of the magazine type comprising a casing serving as a magazine for containing a stack of blades and provided with a blade ejection orifice, means for ejecting blades from the magazine one by one through the blade ejection orifice, a stack of blades in the magazine, each blade being provided with a plurality of nubs on one face thereof spaced longitudinally of the blade, the nubs of the blade being nested in indentations in a contiguous blade, means for resiliently forcing the uppermost blade of the stack into alignment with the path of the plunger and the blade ejection orifice, there being means within the magazine to prevent the cutting edges of the blades from coming in contact with surfaces adjacent to them, the blade ejection orifice being provided with a groove wherein the said nubs may travel as a blade is ejected, and a shaving head having a blade holding channel adapted to be brought into position at which the blade holding channel is in alignment with the blade ejection orifice, the blade holding channel being provided with a longitudinal groove in alignment with the groove in the blade ejection orifice.
